UNITED STATES PATENT OFFICE.

FERDINAND W. MOSTERTZ, OF PHILADELPHIA, PENNSYLVANIA.

PILE FABRIC.

Application filed December 10, 1924. Serial No. 755,051.

This invention relates to weaving and more particularly to the weaving of pile fabric, an object of the invention being to provide a method of weaving fabric with an uncut pile in which two pieces of fabric are woven with their faces together, and are severed or separated without requiring the cutting of the pile and a process or method which eliminates the use of either solid or elastic supports running parallel with the warp threads.

More specifically, the invention comprehends the method of weaving pile wherein certain of the filling threads are positioned outwardly and in proximity to the outer sides of the woven fabric, said filling threads serving as supports for the loops of the pile of the fabric.

Other objects of the invention will appear in the following detail description, and in the accompanying drawings wherein:

Figure 1—is a view showing the longitudinal section on an enlarged scale through the fabric prior to the separation of the two pieces.

Figure 2—is a view similar to Figure 1 showing one of the pieces separated.

Figure 3—is a section through a modified form of fabric on an enlarged scale.

Figure 4—is a section through still another form of fabric on an enlarged scale showing fabric of closely positioned or related piles.

Referring more particularly to the drawings, the fabric shown in Figure 1 is composed of warp threads 1 and 2, which are used in connection with the transverse filling threads 3 in the weaving of the fabric. In weaving the fabric, two sections or pieces of fabric are woven with their faces towards each other, and the pile warp threads 5 of the piece of fabric A are passed through the piece of fabric B and looped over the supporting filling thread 4, and returned to the piece of fabric A forming a pile warp, as shown at 5, and the pile warp thread 5 of the piece of fabric B is passed through the piece of fabric A and over the supporting filling thread 4 thereof, and returned to the piece of fabric B for forming a pile for the piece of fabric B.

By particular reference to Figure 1 of the drawings, it will be noted that the supporting filling threads 4 are placed against the outer surface or sides of the pieces of fabric A and B respectively, and in the pieces of fabric A and B the respective pile warp threads 5 are passed over and under alternate filling threads 3, prior to their return to and through the op-

posite piece of fabric. As shown in Figure 1 of the drawings, the respective pile warp, threads 5 are passed over and under three filling threads before a subsequent pile loop is formed, thus spacing the pile loops at desired predetermined distances apart. After the fabric has been woven, the supporting filling threads 4 are withdrawn which releases the connection of the pieces of fabric A and B and permits them to be separated, leaving the pile loops 5 intact and eliminating the necessity of cutting for the purpose of separating the pieces. In the type of fabric shown in Figures 1 and 2, the pile loops from the two pieces of fabric are placed in parallelism and in lateral alignment with each other. The arrangement of the pile loops in parallelism and lateral alignment with each other is also carried out in the modified form shown in Figure 3 of the drawings. In this form, however, the pile loops 5' are spaced a greater distance apart than in the form shown in Figures 1 and 2, and the warp threads 1' are passed over two and under two of the filling threads, 3. It is understood, in both forms that the warp threads are woven in with the filling threads in the usual manner. The pile loops 5' are passed over supporting filling threads 4', which threads are afterwards withdrawn when the fabric is completed permitting the severing of the two pieces.

In Figure 4 of the drawings, a modified form of fabric is shown in which the pile loops are placed in close proximity to each other, with the pile loops 5^a of the section C of fabric, being disposed alternately to the pile loops 5^a of the piece of fabric D, and it will also be noted in this preferred form, that the supporting filling threads 4^a which are positioned outwardly of the outer surfaces of the pieces of fabric C and D alternately with the filling threads 3^a. The filling threads 4^a are withdrawn after this form of fabric is woven to permit separation of the two pieces of fabric C and D.

It is, of course, to be understood, that the invention may be constructed in various other manners and the parts associated in different relations, and therefore, I do not desire to be limited in any manner, except as set forth in the claim hereunto appended.

What I claim is:

A method of forming pile fabrics, consisting in weaving interconnectingly together two sections of fabric, weaving a plurality of temporary pile supporting threads with

the two sections and positioning the temporary pile supporting threads adjacent the rear faces of the individual webs of fabrics, weaving a series of warp threads to interlace filler threads in each web, then loop over the pile supporting threads at the rear of the opposite web, then return to the filler threads of the first web with which they interlace for a predetermined distance, and again looping said

warp threads over said pile supporting threads, forming a series of loops in each of said fabric sections, paralleling and aligning the series of loops, laterally positioning the loops, and finally withdrawing said pile supporting threads to permit separating of said sections of fabric.

In testimony whereof I affix my signature.
FERDINAND W. MOSTERTZ.
